UNITED STATES PATENT OFFICE.

EDWARD B. ROBY, OF TROY, NEW YORK, ASSIGNOR TO STANLEY M. STONE, OF COHOES, NEW YORK.

DIE AND HEAD FOR FOLDING MACHINES.

Application filed June 21, 1918, Serial No. 241,124. Renewed June 29, 1922. Serial No. 571,793.

To all whom it may concern:

Be it known that I, EDWARD B. ROBY, a citizen of the United States, and resident of Troy, county of Rensselaer and State of New York, have invented certain new and useful Improvements in Dies and Heads for Folding Machines, of which the following is a specification.

This invention relates to dies and heads for use in conjunction with folding machines of the general type described in my Letters Patent No. 1,260,060, issued March 19, 1918, employed for turning the edges of collar, cuff or other blanks composed of fabric.

The invention has for its principal objects to provide a device of the character named which comprises adjustable and interchangeable parts embodying efficient means for turning blanks of a variety of shapes and lengths; which is susceptible of efficient use for alternately turning straight-line and compound-curved blanks; which is used in conjunction with a fixed reciprocating head of a folding machine and is of simple and inexpensive construction, embodying means for extreme accuracy of adjustment and registration of its interchangeable and adjustable parts correlative with said head.

The above named and other objects are attained by employing an elongated head, a plurality of slidably adjustable parts carried by said head, means for adjusting said parts, a sectional die comprising several sections in removable connection with said adjustable parts, pin-means connecting said sections to said adjustable parts, and spring-means for detachably connecting said die-sections with said parts, all as hereinafter fully described and specifically set forth in the annexed claims.

In the accompanying drawings, forming part of this specification, Figure 1 is a side view of my improved head and die. Fig. 2 is a cross sectional view taken on the line 2—2 of Fig. 1. Fig. 3 is a plan view. Fig. 4 is a plan view of one of the end die-sections, drawn on an enlarged scale. Fig. 5 is a cross section taken on the line 5—5 of Fig. 4. Fig. 6 is a side view of one of the sliding tongues; and Fig. 7 is a side view of one of the end die-sections. Fig. 8 is a plan view of the die-head and its tongues. Fig. 9 is a longitudinal sectional view taken on the line 9—9 of Fig. 8. Fig. 10 is a plan

view showing the tongues and dies in register where a straight-line die is employed. Fig. 11 is a similar view showing a compound-curved die; and Fig. 12 is a plan view of one of the die-sections.

In the example of my invention illustrated by the accompanying drawings A, indicates an elongated die-head which has a deep groove 2, extended throughout its entire length. This groove snugly engages rectangular slidably adjustable tongues B, C and D, adapted for detachable connection with the die-sections E, F and G, hereinafter described. The said tongues are respectively provided, at each end, with a lateral groove 3, for engaging lateral extensions h, of spring-bows H, composed of resilient wire; and each tongue has a vertical opening, or passage-way 4, leading through its respective end parts. These passage-ways engage pins 5, of the die-sections E, F and G, which are respectively provided with a lateral notch 6, adapted to register with the slots 3, of the slidably adjustable tongues, whereby the lateral extensions h, of the bows H, may engage said notches and lock the die-sections in place.

The die-sections respectively comprise a base-plate J, having a strengthening rib j, and a thin sheet metal die-plate K, having perforations k, for engaging the pins 5 or their extensions 5^a, and each plate J, has integrally formed tubular studs 7, for fixed engagement with the pins 5 or their extensions 5^a, by means of lateral fastening pins b. When the die-plates are of irregular, or compound curved formation one or more of the pins 5 embody an integrally formed lateral arm 8 and an auxiliary pin 5^a, for direct engagement with a stud 7. This arrangement admits of the employment of my invention for turning blanks of various shapes while at the same time using a perfectly straight-line grooved head and slidably adjustable straight-line tongues, said head maintained in fixed engagement with means for giving it reciprocal motion.

The die-plates K, are fastened to their base-plates J, by means of integral stamped-up tongues 9, which are bent over on the plates J. Thus making a very secure connection without necessity of employing screws which are generally used as fastening means and which are liable to become

accidentally displaced by vibratory action while the device is in operation.

The tongues B and D, are held to the head A, by means of screws L, which pass through slots 1, of the head A; and the tongue C, is secured by means of a screw M, which passes through one of the holes m, in said head.

One side face of the head A, is provided with a scale N; and the tongues B, C and D, are respectively provided with a pointer O, for registering with said scale, whereby the required length of die may be indicated.

The end tongues B and D, may respectively comprise an inverted T-shaped part 10, fixed to the head A, and a rocking part 11, interlocked therewith, one horizontal arm of said T-shaped part normally engaging a slot 12, of the rocking part 11, and the other arm adapted for slidable engagement with a slot 13, of said rocking part 11. These parts are maintained in normal parallel alignment, as shown by Fig. 6 of the drawings, by means of the spring-pressed bolt 14 and the normally contracted spiral spring 15, a shoulder 16, being provided to prevent accidental inward movement of the part 11, while the die is being operated.

By employing the construction hereinbefore described it is noteworthy that the die-plates K, are maintained in secure connection with their plates J, by means of the tongues 9; and accuracy of adjustment between the pins 5 and the tongues B, C and D is attained whether the die-sections K, collectively embody either a straight-line or irregular conformation, said pins 5, being susceptible of perfect registration with the passage-ways 4, of said tongues B, C and D, whether they embody the lateral arms 8 and extensions 5^a or simply straight pins extended from the studs 7.

When a straight-line die is employed, such as shown by Fig. 10 of the drawings, I use all straight pins 5. When a compound-curved die plate comprising the several die-sections shown by Fig. 11 of the drawings is used I employ pins having the offset parts 5^a, which are in register with and engage the perforations k, of the plates K, the parts 5 registering with the holes 4 of the slidable tongues B, C and D. Thus I employ perfectly straight-line tongues B, C and D in conjunction with die-plates of a wide variety of shapes, all parts being interchangeable and susceptible of renewal, in case of breakage, by reason of the fact that the pins 5, in every case register perfectly with the passage-ways 4 and the perforations of the die sections.

In the operation and use of the invention the die is pressed downwardly on and held to the blank to be turned, and the edges of said blank are turned over said die by any suitable means, for instance, the means

illustrated in my Letters Patent No. 1, 260,060. To remove the turned blank the die is contracted in length by swinging the parts 11, downwardly and sliding them inwardly, whereby the blank may be readily removed.

When it is desired to employ a die of another proportion and contour the tongues B, C and D are slidably adjusted and fixed to desired locations within the head A, the sections E, F and G removed and other sections of required dimensions and contour substituted. To remove or attach the die-sections it is simply necessary to expand the bows H, until their extensions h, are out of engagement with the notches 6, of the pins 5.

Having thus described my invention, what I claim as new, and desire to secure by Letters Patent, is:—

1. In a head and die for folding machines, the combination, with a grooved head, and slidably adjustable and detachable tongues within said head, of removable die sections engaging said tongues, and a bow-spring for detachably fastening said die-sections to said tongues.

2. In a head and die for folding machines, the combination, of a grooved head, and tongues slidably and removably engaging said head, said tongues having vertical passage-ways leading therethrough and slots leading into said passage-ways, and bow-springs having extended parts engaging said slots, with removable die-sections engaging said tongues, said die-sections having notched pins extended through said passage-ways and in locking-engagement with said bow-springs.

3. In a head and die for folding machines, the combination, of a grooved head, and a tongue therein, said tongue having vertical passage-ways leading therethrough and slots leading into said passage-ways, and a bow-spring engaging said slots, with a die section comprising a base plate having vertical notched pins, and a die-plate, and means fastening said die-plate to said base plate comprising punched-up tongues formed integral with said die-plate.

4. In a head and die for folding machines, the combination, of a grooved head and a tongue therein, said tongue having vertical passage-ways leading therethrough and slots leading into said passage-ways, and a bow-spring engaging said slots, with a die section comprising a base plate having studs and vertical pins extended therefrom, said pins each having a notch for engaging said bow-spring.

5. In a head and die for folding machines, the combination, of a grooved head, and a tongue therein, said tongue having vertical passage-ways leading therethrough and slots leading into said passage ways,

and a bow-spring engaging said slots, with a die section comprising a die-plate of compound-curved contour, and a base plate having studs and extended pins, said pins each 5 having a notch, one of said studs having a laterally extended arm carrying one of said pins.

6. An interchangeable and removable die-section comprising a ribbed plate having 10 tubular studs, and a die-plate having punched-up tongues engaging said ribbed plate, and notched pins extending from said studs, said die-section adapted for detachable engagement with a sliding tongue of a

15 die-head.

7. An interchangeable and removable die-section comprising a ribbed plate having tubular studs, and a die-plate having punched-up tongues in fixed relation with 20 said ribbed plate, and notched pins extending from said studs, one of said pins embodying a downwardly directed part in direct engagement with one of said studs, a lateral arm and an upwardly extended part, 25 said die-section adapted for engagement with a sliding tongue of a die-head.

8. In a head and die, the combination of a grooved head, and a plurality of slidably adjustable tongues, said tongues having vertical 30 passage-ways leading therethrough, and a plurality of die-sections each comprising a perforated die plate and a perforated base plate, and a plurality of pins, said pins engaging and registering with said 35 passage-ways and perforations whereby all of said parts are interchangeable, and means detachably connecting said parts.

9. In a head and die, the combination of a grooved head, and a straight-line slidably 40 adjustable tongue having vertical passage-ways, and a die-section comprising a die-plate having perforations and a base plate having perforations, with pins extending through said passage-ways and perforations 45 whereby they are in register with each other, and means detachably fastening said pins to said parts whereby all of said parts are interchangeable and removable.

10. In a head and die for folding machines, the combination of a head and slidably adjustable parts, said parts having vertical 50 passage-ways; with die sections comprising respectively a die-plate having perforations and a base-plate having perforations, and pins extending through said passage-ways and perforations whereby they 55 are in register with each other, and means detachably fastening said pins whereby all

of said parts are removable and interchangeable.

11. An interchangeable and removable die-section comprising a ribbed base-plate having tubular studs, and a die-plate having perforations registering with said tubular studs, and means fastening said die-plate to said base-plate, and pins extended through said studs and perforation and fastened to said studs, in combination with a head having a slidably adjustable part, 70 said part having vertical passage-ways for engaging said pins, and means detachably fastening said pins to said part.

12. A die-section having openings extended therethrough, and pins engaging said openings, in combination with a perforated die-plate having its perforations in engagement with said pins, said openings and perforations in register with each other, and means fastening said die-plate and a 75 slidably adjustable part, said pins adapted 80 for removable engagement with a slidably adjustable part of a die head.

13. In a head and die for folding machines, the combination, with a grooved head and a plurality of slidably adjustable parts within the groove of said head, said parts having openings extended therethrough, of a plurality of perforated die-sections, and a plurality of die-plates having perforations registering with said perforations of the die-sections and with said 90 openings, and pins extended through said perforations and openings, and means connecting said parts, said pins in removable engagement with said slidably adjustable 95 parts, whereby the die-sections are interchangeable.

14. In a head and die for folding machines, the combination of an elongated and grooved head, perforated and slidably adjustable parts within the groove of said head, and means for adjusting said parts, with a plurality of perforated die-sections, and a plurality of perforated die-plates, and pin-means extended through said perforated 100 parts, all of said perforations in register with each other, whereby the die-sections 105 are interchangeable.

In testimony that, I claim the foregoing as my invention, I have signed my name in 110 presence of two witnesses, this 14th day of May, 1918.

EDWARD B. ROBY.
